UNITED STATES PATENT OFFICE.

EARL P. OSWALD, OF DETROIT, MICHIGAN.

STEAM GENERATOR.

Application filed March 10, 1923. Serial No. 624,081.

This invention relates to prime movers more particularly of a type somewhat analogous to the steam engine type in which fluid in the form of vapor under pressure 5 is admitted to a power cylinder and thereby made to perform work. The principal object of the invention is involved in the means for maintaining a body of liquid under the desired thermal pressure and discharging 10 the same in predetermined volume per unit of time into a separate heated expansion chamber to cause the same to change in character from a liquid to a gaseous condition and thence delivering it to a cylinder or 15 cylinders in a manner to perform work.

In an ordinary steam engine for instance, the heat applied to the water of a boiler causes steam to rise from the surface into what is known as a steam dome from which 20 the steam is discharged to cylinders in the well known manner. The pressure release in the steam dome caused by the use of steam reduces the pressure on the body of liquid in the boiler resulting in certain volume 25 changing into steam to maintain pressure. In my invention the fluid which may be water or other volatilizable liquid is maintained in a chamber that is completely filled with the liquid and in which the heat is 30 applied thereto to produce the desired thermal pressure, means being employed to supply this chamber with liquid under mechanical pressure preferably greater than the thermal pressure. The quantity of fluid to 35 be utilized in operation of the engine is withdrawn from this boiler chamber in liquid state and discharged to a separate expansion chamber from which the cylinders take their power supply as is hereinafter described. 40 The vapor or steam generator herein disclosed is designed and adapted for use in conjunction with an engine as a power plant for automotive vehicles for which purpose compactness in form is necessary and therefore 45 an object of this invention is to provide an engine of the general character stated in which the boiler element is small and compact in form and provides such an element in intimate association with the power cylinders in such way that the entire power plant including the cylinders and 50 boiler element may occupy space not mate-

rially greater than that occupied by an internal combustion engine of similar horsepower.

A further object of the invention is to provide means in conjunction with a boiler element whereby the heat applied to the boiler is automatically controlled by the vapor temperature in the expansion chamber. 60 This is an essential characteristic of the invention when utilized as a power plant for automotive vehicles and is preferably utilized even though the boiler or vapor generator be used for stationary power purposes. 65

Further objects and features of the invention are in provision of means for maintaining the boiler filled with the liquid at the desired mechanical pressure and which automatically by-passes the liquid when the pressure in the boiler is greater than the pressure for which the apparatus is set to maintain in the boiler chamber. The power plant may be utilized with various liquids as for instance water, sulphur dioxide (SO₂), carbon tetrachloride (CCL₄), the latter fluid boiling at 143 degrees F., and freezing at ten degrees below zero. Whatever the liquid used, however, there is a closed cycle therefor, it being drawn from the liquid supply source, discharged to the boiler member, thence to the expansion chamber, thence to the engine and then exhausted to a condenser from which it is returned to the supply source. A 70 feature of this invention is involved in the general arrangement of parts permitting such closed cycle flow and the means employed for maintaining the fluid in the supply source at above normal pressure. 75

An additional object of this invention is to provide a steam or vapor generator and power element in which the gases of combustion are made to flow about all steam or vapor conduits up to and including the power element whereby the vapor or steam does not suffer loss of heat until utilized and passed from the power element. 85

These and various objects and novel features of construction involved in this invention are hereinafter more fully described and claimed, and the preferred form of construction of a power plant including a steam or vapor generator embodying my invention 100

is shown in the accompanying drawings in which—

Fig. 1 is a plan view, partly broken away, of an engine embodying my invention.

Fig. 2 is a section taken approximately on line 2—2 of Fig. 3.

Fig. 3 is a vertical section substantially on the line 3—3 of Fig. 2.

Fig. 4 is a diagram or flow sheet showing the boiler and circuit of the fluid from the liquid supply through the boiler and engine and returning to the liquid supply.

Fig. 5 is a vertical section of a fuel burner adapted for use with my improved vapor generator.

Fig. 6 is a detail in vertical section of a valve in the by-pass.

Fig. 7 is a side elevation partly in section of the control means for the engine valve.

Fig. 8 is a section taken on line 8—8 of Fig. 7.

Fig. 9 is a section taken on line 9—9 of Fig. 8.

Fig. 10 is a section of the eccentric rings.

Fig. 11 is a detail in perspective of the block riding in the eccentric rings.

Fig. 12 is a detail in perspective of the actuator for the rings.

Fig. 13 is an elevation showing a means in addition to the thermostatic control for controlling the fuel valve.

In this invention and in order to secure a boiler of small compass, a comparatively small body of the volatilizable liquid only is heated to the desired degree and this liquid is replaced as rapidly as it is withdrawn thus maintaining the liquid in the boiler under a constant pressure and the steam or vapor under pressure is produced by withdrawal of a small quantity of fluid and discharge of the same into an expansion chamber separate from the liquid or heating chamber and differs in this respect from any other apparatus utilizing an expansible or vaporizable liquid for the operation of an engine.

With a steam boiler a large quantity of water is maintained under the necessary degree of heat to produce steam and removal of the steam from the steam dome of the boiler reduces the pressure momentarily to a greater degree than the removal of the quantity of the liquid to produce the steam would reduce the boiler pressure and an economy in operation is effected by withdrawal of liquid

rather than the vapor. The boiler or generator structure is shown in section more clearly in Fig. 3 and consists of a shell preferably of phosphor bronze as the same will stand considerable heat and the rapidity with

which it transmits heat is greater than that of iron usually used in boilers. This boiler is designated generally by A and comprises an inner hollow member 2 having a cone shaped wall, an intermediate shell 3 providing a space 4 between the shells 2 and 3, and

an outer shell 5 providing a space 6 between the shells 3 and 5. This entire body is heat insulated by asbestos or similar heat insulating body indicated at 7 about which is a sheet metal shell 8 for holding the same in place.

The space 4 is the heating space of the boiler and a burner indicated generally at 9 is provided at the small end, the shell 3 having a cylindrical neck 10 into which the forward end of the burner slightly projects.

The forward end of the shell 2 is rounded as indicated at 11 and this, as before stated, is cone shaped so that the flame emanating from the burner passes about this rounded point

11 and through the cone shaped passageway or space 4 subjecting the entire cone shaped wall 2 of the inner member to the heat and also subjecting the wall 3 to the heat of the flame.

By making this member cone shaped as stated, it may be less in length for the reason that if it were cylindrical a much longer passageway would be required to insure absorption of heat of the flame by the walls of the boiler before passing from the boiler.

By the cone shape shown, the area of the walls 2 and 3 rapidly increases toward the base of the cone, the heat absorption thus being increased as the flame progresses from the point toward the base.

The inner cone member 2 is hollow as stated providing a chamber 12 hereinafter termed the "expansion" chamber and a series of ribs 13 are provided extending from the point 11 toward the rear end of the chamber 12 and these are utilized to transmit the heat of the flame from the point to the interior of the expansion chamber.

The base of the chamber 12 has an opening closed by the conical member 14 flanged at 15 to be secured to the inwardly extending part 16 of the wall 2.

This member 14 carries a needle valve 17 movable longitudinally of the recess 20 provided therefor, and this needle valve controls the orifice 18. This cone member 14 also has a conduit 19 leading to the chamber 20 about the needle valve in communication with the orifice 18.

This conduit 19 in the member 14 is connected by means of piping 21 with the space 6 which contains the liquid heated by the flame from the burner 9.

As will be hereinafter described, liquid is maintained in this chamber 6 under pressure and is maintained comparatively full of liquid including the piping 21 and conduit

19 and chamber 20 about the needle valve.

With this chamber continuously supplied with liquid under pressure at least equal to but preferably greater than the desired thermal pressure—say five hundred pounds per

square inch and considering the liquid is under three hundred pounds thermal pressure—the opening of the valve 17 will allow liquid to flow through the orifice 18 into the expansion chamber 12. Pressure being thus

suddenly released, the fluid is immediately

115

100

105

130

converted into vapor and this flows from the orifice 18 toward the point of the member 2 and across and into intimate contact with the ribs 13 which transmit the heat to the interior of this chamber 12 and thus it is super-heated in this chamber 18.

As hereinafter described, this vapor is transmitted to the engine cylinders which operate after the manner of the usual steam engine. A feature of the invention is in maintaining the pressure of the liquid in the boiler and releasing the liquid in a separate expansion chamber subject to the heat of the gases of combustion and also separate therefrom. The pressure of the vapor therefore has no effect whatsoever on the liquid and the vapor is thus not withdrawn from the liquid body in the boiler but only the liquid having the desired thermal pressure and this vapor is in fact superheated in this chamber 12 due to its coming into intimate contact with the heated wall 2 and ribs 13 as above described.

To enable this structure to be utilized efficiently, I have provided an engine structure with which it is closely associated, and this engine consists of a casing 22 in which is mounted the crank shaft 23 having the usual crank 24 as will be understood in Fig. 2 which is connected by means of a connecting rod 25 with the piston 26 in the cylinder 27. There are two such cylinders here shown—27 and 27^a although it is to be understood that any number of cylinders may be utilized. As these cylinders are similar in construction, a description of one is deemed sufficient for the purpose of this specification.

The cylinders are each provided with a similar slide valve on one side thereof as will be understood from Figs. 1 and 3. This is also indicated at 30 in Fig. 4 and may be operated in any approved manner as by an eccentric 31 having an arm 32 connected with the eccentric band at the shaft end and provided at the upper end with a bar 33 connecting the same with a stem 34 of the valve. This valve is hollow in the construction as here shown and as is indicated at 35 and is provided with rings at opposite ends riding in the case 36 on the side of the cylinder which is ported at 37 and 38 at opposite ends of the cylinder. A central inlet port 39 is provided which is connected by means of a conduit 40 with the interior of the expansion chamber 12. Thus, vapor under pressure is supplied to the valve which in its reciprocation first connects the central portion 39 with the port 38 and then closes it to the port 38 and opens it to the port 37 which causes reciprocation of the piston. When the inlet port 39 is closed to the port 38 by movement of the valve upward in its chamber, the port 38 becomes open to the hollow interior 35 of the valve,

and when the port 37 is open to the casing in which the valve reciprocates. To this valve casing is connected the exhaust piping 41 and exhaust steam or vapor is thus passed from the cylinder to this piping 41 to the upper end 42 of a radiator 43 which may be of any approved character of construction and is here shown as a series of vertical tubes open to atmosphere by the vapors cooled and condensed in the tubes. The tubes are open at the upper end to the chamber 42 at the head of the condenser and at the lower end to the supply tank 44 into which the condensed liquid falls. The circuit of the vapor flow is shown graphically in Fig. 4 and preferably this tank 44 is covered with heat insulating material 45 to prevent loss of heat of the fluid therein. A supply pipe 46 leads into this tank 44 and to a pump which is shown in the diagram as a reciprocating pump 47 connected with the end of the valve so that reciprocation of the valve operates the pump. This arrangement, however, is merely diagrammatic in order that the flow sheet will be perfectly clear. The structure of the pump is shown more clearly in Fig. 2 and is hereinafter described. From the pump the fluid is transferred by means of a pipe line 48 to the space 6 of the boiler member. A by-pass is provided between the pipe line 46 and 48 adjacent the pump in which is a spring check valve 49 set to operate at predetermined pressure. This valve is preferably set at about five hundred pounds pressure as the thermal pressure is usually between three and four hundred pounds in the boiler. Therefore the normal thermal pressure may not force the fluid back from the boiler. It is to be noted, however, that should the pressure in the boiler rise above that for which this valve is set, the check valve allows the water of the boiler to pass back into the tank 44.

The pump 47 is shown more clearly in Fig. 2, and it is to be noted that the crank shaft 23 is provided with two cranks 50 and 51 and a block 52 is provided on each crank 2 riding in a yoke 53 to which the pump plunger 54 is connected. This is an ordinary plunger pump and the piping 46 leads to an orifice of the pump and the piping 48 leads to a similar orifice on the opposite side of the pump case. There is a check valve provided at the intake side opening on the intake stroke and closing on the exhaust stroke of the plunger and a similar check valve at the discharge orifice closing on the intake stroke and opening on the discharge stroke of the plunger all as is the usual practice with plunger pumps. By use of two pumps as stated, and as will be understood from the drawings, a practically continuous pressure is provided in the line 48 leading to the boiler and, as previously stated, a similar pump is shown in the flow

sheet merely for a purpose of illustration of flow. Fig. 2 is the half section and shows only one of the pumps but the other pump is exactly similar and is connected with a similar yoke on its respective crank, and the discharge and intake orifice of the second pump are likewise connected with the piping 46 and 48.

In order to secure compactness of the engine and boiler structure, I mount the boiler above the crank case and between the two cylinders as will be understood from the drawings particularly Fig. 2. These cylinders are positioned at an angle one to the other thus providing space between the cylinders to mount the forward end of the boiler therebetween. For this purpose a bracket 55 is mounted on the forward end of the crank case and provided at the upper end with a cylindrical portion 56 in which the forward end 10 of the boiler structure rests and on this bracket is mounted the burner member 9 hereinafter more fully described and by means of which intense flame 25 is directed into the heating space 4 of the boiler. This boiler member is preferably covered with insulation 7 as previously stated and a metal shell thereabout. At the rear and large end of the boiler it is to be noted that the space 4 opens through the end thereof, there being webs 56 supporting the wall 3 relative to the inner wall 2 of the structure, the arrangement permitting flame and heated gases of combustion to pass freely into a chamber 57 provided at the rear end of the boiler. This chamber is formed by insulating material 58 enclosed within sheet metal cover members 59, and this structure providing the chamber 57 may be secured to the rear end of the boiler by means of a series of bolts, one of which is shown at 60 in Fig. 3.

It will be noted from Figs. 1 and 2 that the cylinders 27 and 27^a are surrounded with a sheet metal or heat insulating wall 61 spaced from the cylinder in each case. A conduit 62, shown particularly in Fig. 1, leads from this chamber 57 to the casing 61 surrounding the cylinder and valve chamber, and an outlet conduit 63 is provided from the casing 61. The products of combustion thus pass from the oil burner 9 through the combustion space 4 of the boiler to the chamber 57 and thence about the vapor conduit 40 to about each cylinder and are then passed to atmosphere through the conduit 63 and thus conserve the heat of the gases of combustion to the greatest possible extent. Thus, all the parts carrying steam or vapor are shielded within the conduit for heated gases from the expansion chamber to atmosphere. The exhaust conduit 41 for the steam or vapor from the cylinders is not insulated as it is desired to condense the vapor immediately upon discharge from the work

cylinder. The fluid in the boiler member or steam or vapor after its expansion is so shielded as to prevent radiation of heat.

The preferred fuel for this engine is oil such for instance as kerosene and the burner 70 consists preferably of a hollow member 9 open at the forward end which, as is shown particularly in Fig. 3, is positioned in the neck 10 of the boiler member which is open to atmosphere, there being a space 65 between the member 9 of the burner and the neck 10 of the boiler. This space is open to the cone shaped combustion space 4 of the boiler. The flame is like that of a torch blowing directly against the point 11 of the wall 2 and the flame is directed equally about the member 2 in the space 4. Velocity of flow of the combustion gases by the arrangement here shown decreases toward the large end due to the greater space to be occupied thereby and giving ample opportunity for absorption of heat of these gases as they pass through the boiler to the chamber 57 and conduits 62. I have here shown a special form of burner adaptable for the purpose, but it is to be understood that any type of burner may be utilized. As here shown, the burner consists of the member 9 which is formed of a hollow shell open at the forward end and provided with a rib 66 across the lower side thereof and what I have termed a chimney 67 which is semi-circular in form passing about this rib or boss 66 on the lower side of the burner. This member 67 has an opening at the bottom common to the two sides 67 and 67^a to which the lamp 68 may be connected. This lamp 68, as shown in Fig. 5, consists of a receptacle having a central tubular member 70 extending centrally therethrough about which is a cylindrical wick 71 extending down into the oil receptacle. The wick may be turned up or down by the usual wick adjuster 72. The upper part of the member 68 is provided with a cylindrical portion 73 having a bayonet slot 74 therein on opposite sides to engage a pin 75 on the lower end of the member 67 and 67^a by means of which the receptacle may be secured to or removed from the chimney member. In this receptacle 69 is a hinged float 76 carrying a valve 77 controlling the flow of oil into the chamber 69 from the pipe 78. This pipe 78 is preferably connected directly with the fuel tank 80. This fuel tank may be located in any desired position as for instance above the burner as shown in Fig. 4, and a pump (not here shown) may be provided by which pressure may be produced in the fuel tank so that the fuel flow is under pressure. By means of the float 76 in the oil receptacle the level of oil is maintained practically constant therein. The line 79 leads to a conduit 82 in the rib or boss 66 on the under part of the member 9 and the conduit leads

to a vertical conduit 83 formed in the casting at the rear end of the member 9 and opening to a discharge orifice 84 in the rear wall of the member 9. This orifice is controlled by a needle valve 85 as indicated in Fig. 3. This valve may be of any desired type controlling the volume of flow of fuel into the burner and may be manually controlled if desired or found practicable as may also the valve 17 controlling the flow of liquid from the boiler 6 to the expansion chamber 12. It is, however, preferable that the oil flow to the burner be controlled either by the pressure of the fluid in the space 6 of the boiler or by the temperature of the vapor in the expansion chamber 12. Either or both means may be employed and to increase the safety factor I prefer to provide both control means for the fuel flow for the valve 85. One means is shown plainly in Fig. 3 and consists of a chambered member 86 secured to the rear end of the casting providing the burner member 9. This casting has an aperture for the member 85 which is freely reciprocable therein and the rear end of the casting is flanged as indicated at 87 to receive the similar flange in the end of the member 86. In this member 86 is a disk 88 and this disk has two concentric corrugated or bellows like members 89 and 90 secured thereto forming a chamber therebetween closed by the disk 88 at the one end, and by a plate 91 at the outer end. Therefore, this chamber between the two bellows members 89 and 90 is a sealed chamber indicated at 92. The needle valve stem 85 is secured to the member 88. This member 88 within the inner corrugated or bellows member 90 is provided with a rod 93 extending outwardly through the member 91 which is secured to the outer end of the member 86. A spring 94 is provided thereon, as will be understood from Fig. 3, which extends to open the valve 85 allowing full flow of fuel within the capacity of the orifice 84 into the burner.

It is to be noted that an aperture 95 is provided in the wall between the chimney 67 and the member 9 which will permit flame from the wick member to pass into the interior of the member 9 in position to ignite fuel supplied thereto through the orifice 84. It is also to be noted that there are a number of apertures 96 in the member 9 at the rear end permitting ingress of air which is drawn thereinto by flow of the fuel through the member 9. Thus the member 68 and chimney therefor provide a pilot light and also tend to maintain the oil conduit 89 heated which is the preferable condition under which to burn various fuel oils. With the valve 85 open to a greater or less extent, fuel is forced under pressure into the burner which is ignited and the flame is blown into the combustion space 4 of the burner, suf-

ficient air being drawn through the apertures 96 and the space 65 to produce practically complete combustion.

Preferably the flow of fuel is thermostatically controlled and this is accomplished in the following manner: In the interior of the expansion chamber 12 at the rear end thereof toward which the vapor flows on its way to the conduits 40 and thence to the work cylinders, is a chamber 100 sealed to the expansion chamber 12 and to this chamber is connected a conduit 101 leading from the rear wall of the expansion chamber through the chamber 57 for heated gases and along the outer wall of the boiler covered by the insulating material 7 and leading to a boss 102 on the plate 91. This boss has a channel leading to the space 92 between the bellows members 89 and 90 and this conduit from the boiler to the plate 91 may be heat insulated if desired. This space 100 and the conduit 101 and the chamber 92 is practically filled with a volatile fluid and, inasmuch as the chamber 100 is subjected to the heat of the expanding vapor in the chamber 12, the fluid in the chamber 100 and the conduit and chamber 92 tends to expand forcing the disk 88 in a direction to close the valve 85 against the tension of the spring 94. As heretofore stated, this boiler is preferably operated at between 300 to 400 pounds thermal pressure. To operate at 300 pounds thermal pressure, a heat of approximately 424 degrees F., is required and the valve 85 and the spring 94 may be so adjusted as to require about 300 pounds pressure to close the same, less pressure only partially closing the valve as will be readily understood. Thus, as the thermal pressure in the boiler rises to about 300 pounds, the fluid in the chamber 100 will tend to close the valve. This fluid may be oil or a mixture of volatile liquids that are expanded to the desired degree and shut the valve 85 when the desired thermal pressure of the boiler is secured—that is, if 300 pounds thermal pressure of the boiler is the limit at which it is desired to operate the same and 424 degrees F., is the temperature of the vapor in the expansion chamber to which the fluid in the thermostatic shell 100 is submitted, then the said fluid should have a sufficient expansive force at that temperature to close the valve. As shown in Fig. 13, in addition to the thermostatic control above specifically described, an additional direct pressure may be employed and this is exactly identical in structure and is carried to the stem 93 so that certain pressure being attained in the chamber 105 of the pressure device, the valve 85 will be closed. This chamber 105 is connected directly with the boiler space by a conduit 106 leading from line 48 as shown in Fig. 2 and it may be set to operate at a somewhat higher pressure than the thermostatic control device is

set to operate and thus if, for some unknown reason, the thermostatic device fails to operate by forcing the plate 88 forward to close the valve 85 then, as the flame continues and the boiler pressure increases, this pressure will be communicated to the chamber 105 and operate the valve to close the same. A double factor of safety is thus provided in the control of the flow of fuel to the boiler and this is in addition to the safety factor provided by the bypass between the lines 46 and 48 so that excess pressure in the boiler can still be relieved through the valve 49. Thus, by provision of these safety devices, if the engine be standing still and the flame and fuel flow be at full degree, practically all the fluid in the boiler member may be driven therefrom without the pressures increasing beyond ordinary safe limits.

As heretofore stated, this boiler member and engine differ in many respects from an ordinary steam engine yet the engine operation is practically identical with that of the steam engine whereby the usual power transmission structure, clutch, etc., employed with an internal combustion engine driven vehicle may be dispensed with. The boiler differs from any ordinary steam boiler even though water be used and in this respect in the ordinary steam boiler, steam is withdrawn for use in the engine. With this device the liquid is withdrawn and is continuously supplied as fast as withdrawn under a pressure in excess of thermal pressure of the boiler. Thus, a boiler structure that is small and compact and yet highly efficient is secured. Upon the opening of the valve 17 and due to the high thermal and mechanical pressure under which the liquid enters the expansion chamber 12, it immediately expands into vapor and by reason of its being blown directly into contact with the heated fins 13 and interior wall 2 of a combustion space of the boiler it acts to take up heat therefrom due to its expansion. It will be observed that the liquid under the thermal and mechanical pressure, upon expansion, would be cooled but, by expanding the same in the heated chamber 12 the walls of which are of high thermal conductivity, the heat from the combustion space is taken up by the steam and thus the same is heated to a degree depending upon the period of time which the vapor remains in the expansion chamber. This period is determined by the work cylinders to which the vapor or steam passes from the chamber on its way to atmosphere. With the engine idling doing no particular work, the steam flow may be comparatively rapid from this chamber 12 to the work cylinders and to atmosphere. If work is to be accomplished by the movement of the pistons in the cylinders, a resistance to the flow of steam or vapor from the expansion chamber is pro-

duced and this tends to delay passage of the steam from the expansion chamber causing it to take up more heat and to increase the pressure as the work demands. Thus, with little or no work to be accomplished, the vapor or steam passes readily from the expansion chamber but, as resistance to flow occurs, the temperature in the expansion chamber will tend to fall due to more rapid absorption of the heat. This affects the thermostatic control and will tend to open the fuel valve and increase the flow of fuel and upon cessation of the work effort of the cylinders, the temperature in the expansion chamber will tend to increase raising the temperature of the fluid in the thermostatic cell and pipe line 101 and tend to close the valve 85 and restrict the amount of fluid supply.

The power element described in conjunction with the boiler is of the reciprocating steam engine type and is here illustrated merely to show a means of translating the pressure of the vapor into effective work but any type of vapor pressure translating device may be utilized in the outlet conduit for the expansion chamber 12 and, as heretofore stated, this pressure translating device provides a resistance to flow of vapor under pressure from the expansion chamber whereby effective work may be accomplished. The reciprocating type of engine, however, is a serviceable type and may be utilized as here shown with the two cylinders at an angle one to the other with a boiler member located therebetween in order to secure a compact structure and in which case the chamber for the products of combustion at the rear of the boiler is connected to both the shells surrounding the cylinders by a conduit and the conduit for the expansion chamber is located in the interior of the exhaust conduit for the gases of combustion. Compactness is also secured principally by the character of boiler structure and its mode of operation. The boiler structure is preferably of cast metal and cone shape form as hereinafter stated provided with an outer liquid chamber and an inner expansion chamber of cone shaped form and a narrow cone shaped combustion space or chamber between the liquid and the expansion chambers. The liquid chamber by reason of the continual supply of fluid as fast as it is removed from the liquid chamber may be of small capacity, as for instance about a gallon of liquid for an engine of a size adaptable for use in an automotive vehicle. Naturally power plants of greater capacity will require liquid chambers of greater capacity and other parts proportionately larger. The liquid is supplied to the liquid chamber preferably at the forward end by the conduit 48 and this inlet to the liquid chamber is near the point of greatest heat

- application as will be understood from Fig. 3. The liquid is withdrawn from the liquid chamber at the rear end so that inflowing liquid, from the time of its introduction 5 into the liquid chamber at the forward and lower side of the boiler member to the time of its discharge from a point at the upper rear end thereof, has ample time to heat to the desired degree.
- 10 As has been previously stated, I preferably employ a burner of the blowtorch type utilizing preferably a liquid hydrocarbon fuel and a structure of a burner is here shown adaptable for the purpose, the features of 15 which will be embodied in a separate application for patent. This invention, however, is not limited to the particular type of burner or the particular type of pressure translating device.
- 20 The valve controlling the flow of liquid to the expansion chamber is here shown as being of the needle type. The invention, however, contemplates the use of any valve adaptable for the purpose, and this valve is independently and preferably manually controlled 25 while the application of heat to the boiler is preferably automatically controlled. The liquid and vapor has a closed circuit as heretofore stated and therefore there is no 30 loss of liquid due to there being no exhaust to atmosphere and the special type of liquid utilized may be even more expensive in character and still economical in use due to this fact.
- 35 In an engine of this character, this slide valve 30 is operated by an eccentric 31 shown in Fig. 4. This Fig. 4, however, is diagrammatic in form and an ordinary eccentric is there shown. In order to manually 40 change the throw of the valve or to reverse the engine, this eccentric 31 is preferably constructed as shown in detail in Figs. 3 and 7 to 12 inclusive. This may be accomplished by means of a shaft 107 extending through 45 the crank case as shown in Figs. 3 and 7, and an operating lever (not here shown) utilized on the exterior of the crank case by which an operator may control the throw 50 of the eccentric and thereby vary the speed of the engine or reverse the same in operation. The shaft 107 has a fork 108 attached thereto, one arm of which is shown in Fig. 7 and the arms are connected to a ring 109 riding in a cylindrically grooved portion 55 110 of a shift block which consists of the said member 110 and blocks 111 and 112 which have parallel inclined faces 113 and 114 respectively. The member 110 has a cylindrical aperture 115 for the shaft 23 and is loose on the shaft and movable by the rock arm 108. As shown in Figs. 8 and 10, the eccentric 31 has a rectangular aperture there-in and is formed of two blocks 31^a and 31^b which are riveted or secured together and are 60 flanged as will be understood from Figs. 7 and 10 providing a cylindrical groove for a ring 116 preferably formed of two parts 116 and 117. This ring member has an arm 118 pivotally connected with the arm 32 by means of a pin 119. As previously stated 70 this arm or rod 32 is connected with the valve stem 34 by means of an arm 33, the preferred mechanical arrangement being shown in Fig. 1 and diagrammatically in Fig. 4. The position of the blocks 111 and 112 longitudinally 75 of the shaft relative to the member 31 determines the eccentricity of the member 31 relative to the shaft as will be understood from the following:—Keyed to the shaft 23 is a block 120 shown particularly in Figs. 80 8, 9 and 11. This block is rectangular in form and has a groove 121 and 122 upon the upper and lower faces for the inner faces of the members 111 and 112. The member 31 has a rectangular aperture therein greater 85 in length than the block and these two members 31^a and 31^b, as shown in Fig. 10, are formed with a vertical groove 123 on opposite vertical faces providing a way for ribs 124 and 125 on the block 120. These members 31^a and 31^b also have a groove 126 and 90 127 in the upper and the lower wall respectively of the central rectangular, aperture, the bottoms of which grooves are inclined relative to the axis of the shaft and in parallel relation against which the faces 113 and 114 of the blocks ride. By this arrangement, movement of the member 110 and the two blocks thereon toward the right of Fig. 7 would tend to move the member 31 95 downward relative to the shaft 23 with the axis of the member 31 eccentric to the axis of the shaft, and movement in the opposite direction will tend to produce the opposite eccentricity so that on revolution of the shaft 100 and the member 31, the eccentric rings would function to reciprocate the rod 32 and depending upon eccentricity the varying speeds of the engine operation may be secured or the engine reversed in its direction of operation 105 as will be readily understood by those familiar with the slide valve type of engine.
- 110 The above described eccentric is of a particular form and preferably is the type utilized with this particular type of motor. It will be understood, however, that any character of mechanism adapted to operate the valve may be utilized without departing from the spirit of this invention.
- 115 From the foregoing description it will become evident that the principal features of this invention are involved in the boiler structure and its mode of operation and in the maintenance of the vapor under the influence of the heated gases up to the time of its exhaust from the engine with which it is to be utilized and thereafter condensed and returned to the boiler in liquid form for subsequent use. It is further evident that the 120 boiler structure, due to its mode of opera- 125
- 130

tion in the production of steam for use in a work cylinder and due to its particular form, a large percentage of the heat of the gases of combustion may be absorbed in a combustion chamber of comparatively short length and that the various novel features of the invention, as hereinbefore pointed out, are secured by a construction that is simple and inexpensive in character.

10. Having thus fully described my invention, what I claim and desire to secure by Letters Patent of the United States is—

15. 1. A boiler for the production of vapor under pressure for operation of a power element comprising a substantially cone shaped member formed of metal of comparatively high thermal conductivity, said member having an exterior chamber for liquid and a separate interior chamber for 20 vapor, a passageway between the liquid and vapor chambers cone-shaped in form into which products of combustion are discharged from the small end, a chamber having a discharge orifice for the heated gases 25 of combustion at the large end of the cone-shaped passageway therefor, a conduit in the said heated gas chamber extending between the liquid and vapor chambers, a valve for regulating the flow of liquid into 30 the vapor chamber, and a discharge conduit for the vapor chamber, means for discharging liquid into the liquid chamber under a pressure in excess of thermal pressure therein, and means controlled by the temperature 35 of the vapor in the vapor chamber for regulating the flow of fuel to the burner.

2. A boiler for the production of vapor under pressure comprising a cellular structure of a metal of high thermal conductivity having substantially the form of a cone and provided with an outer cell or chamber for liquid and an inner cell or expansion chamber for vapor open to permit flow of vapor therefrom, the outer chamber being 45 spaced from the inner chamber providing a

combustion chamber of coned form, the expansion chamber having an outer rounded small end, a burner of the blowtorch type, the flame of which impinges directly upon the small end of the expansion chamber deflecting the products of the combustion into the cone-shaped combustion chamber, there being webs of metal extending from the point toward the rear of the interior of the expansion chamber, a discharge orifice at the rear of the expansion chamber discharging in the expansion chamber directly toward the point and webs of metal, a conduit connecting the liquid chamber with the said discharge orifice of the expansion chamber, a valve controlling the flow of liquid to the expansion chamber.

3. In apparatus of the character described a boiler member for the production of vapor under pressure, the boiler member having an outer chamber for liquid and an inner expansion chamber for vapor and a passageway therebetween providing a chamber for the gases of combustion, a heating device discharging the products of combustion through the combustion chamber, a conduit for the products of combustion at the end of the combustion chamber, a conduit subject to the heat of the products of combustion leading from the liquid chamber to the vapor chamber, a valve for controlling the flow of liquid therethrough, a conduit from the expansion chamber located within the said conduit for combustion gases, means whereby liquid is supplied to the liquid chamber under pressure in excess of the thermal pressure of the liquid in the liquid chamber, and means for controlling the heat appliance preventing the production of the thermal pressure in excess of a predetermined amount.

In testimony whereof, I sign this specification.

EARL P. OSWALD.
